UNITED STATES PATENT OFFICE.

FREDERIC SCHOFF, OF PHILADELPHIA, PENNSYLVANIA.

PORTABLE REAMING AND TAPPING TOOL.

SPECIFICATION forming part of Letters Patent No. 437,459, dated September 30, 1890.

Application filed July 9, 1890. Serial No. 358,208. (No model.)

To all whom it may concern:

Be it known that I, FREDERIC SCHOFF, a citizen of the United States, and a resident of Philadelphia, Pennsylvania, have invented 5 certain Improvements in Portable Reaming and Tapping Machines, of which the following is a specification.

The object of my invention is to construct a portable reaming and tapping machine that 10 will be simple in construction and that is readily interchangeable and specially applicable to flexible shafting, the machine being reversible, so that the tool can feed forward or reversed, as fully described hereinafter.

15 In the accompanying drawings, Figure 1 is a perspective view of my improved reamer. Fig. 2 is a sectional plan on the line 1,2, Fig. 4. Fig. 3 is a longitudinal section on the line 3,4, Fig. 2. Fig. 4 is an end view looking in 20 the direction of the arrow, Fig. 2. Fig. 5 is a view of a modification of my invention, and Fig. 6 is a view of a tool-carrier.

A is the casing of the machine, made in the peculiar form clearly shown in Fig. 2, and 25 mounted on the casing is a cap A', secured thereto by bolts and screws a a. An extension A² of the casing forms a bearing for the driving-shaft B and also affords a hand-hold for the operator. On the opposite side of the 30 casing is a handle a', which can be grasped by the operator. On the outer end of the shaft B is a coupling b for the flexible shaft x. (Shown in Fig. 1.) On the inner end of this shaft is a gear-wheel D, which is detachably 35 secured to the shaft. This wheel meshes with a pinion E on the shaft F. The pinion in the present instance is secured to the shaft, and also secured to the shaft is a worm E'. In 40 some cases the pinion and worm may be made in a single piece, and when this is the case the worm and pinion need not be secured to the shaft, being merely mounted thereon, or they may form the shaft. Meshing with the worm is a worm-wheel G on a spindle H, which 45 has its bearing in bushing in the casing and in the cap A'. This spindle H has in the present instance two tapered orifices h h', as shown in Fig. 3, one extending from one end of the spindle and the other extending from 50 the other end of the spindle. To either one of these orifices is adapted the tool or tool-carrier I, Fig. 6, as the case may be.

The openings I' in the tool-carriers are of different diameters, in order to accommodate different-sized heads of tools. The orifices h 55 h' in the spindle may be made to fit regular-sized tools, and a sleeve J (shown by dotted lines in Fig. 3 and in full lines in Fig. 5) may be used for larger or smaller tools. The sleeves J can be screwed onto the threaded portions 60 of the spindle, as shown.

On each end of the spindle I prefer to place nuts i i, as clearly shown in Fig. 3. These nuts are for the purpose of forcing the tools or their holders out of the sockets when it is 65 wished to remove them from the machine.

The main shaft B and the spindle H are in line with each other, so that the rotary motion will not affect the grasp of the operator.

On removing the cap and replacing the pinion and gear-wheel with wheels of different diameters different speeds can be obtained, and in some instances the worm and worm-wheel may be changed to worm and worm-wheels of different pitch. 70

75 By the above-described mechanism I am enabled to reduce the high speed of a flexible shaft to the speed required for reaming or tapping, the parts being simple in construction, and can be readily and accurately made 80 and repaired with very little cost.

The operation of the machine is as follows: The coupling b is secured to the flexible shaft x and tool mounted in one of the spindle-openings h. The machine is then held in the hand 85 in the position shown in Fig. 1, the projections A² and a' being grasped by the operator. After the reamer or tap has been fed forward the machine can be turned over and the opening h' of the spindle placed over the head of 90 the reamer or tap, and consequently on motion being applied to the machine the reamer or tap will be reversed and withdrawn.

In Fig. 6 I have shown a solid spindle secured to the worm-wheel and screw-threaded 95 at each end, one end having a right-hand screw and the other end a left-hand screw. Adapted to these screw-threaded ends are hollow tool-carriers or sleeves J, described above, which secure the head of the tool. 100 These carriers are made in a number of sizes for different-sized taps or reamers.

I claim as my invention—

1. The combination, with the portable ream-

- ing or tapping machine, of the casing, the shaft B, mounted therein, having at its outer end a coupling for a flexible shaft, a gear-wheel mounted on said shaft, a longitudinal shaft H, having a pinion and worm E', said pinion gearing with said wheel and a worm-wheel meshing with said worm, and a tool-spindle on which the worm-wheel is secured, substantially as described.
- 10 2. The combination of the casing A, the cap A' secured thereto, an extension A², a driving-shaft mounted in said extension, a handle a' opposite said extension A², a tool-spindle, and gearing connecting said spindle with the driving-shaft, substantially as described.
- 15 3. The combination of the casing, the driving-shaft, the worm-wheel, the worm, and gearing connecting said worm-wheel with the driving-shaft, a spindle on which the worm-wheel is mounted, and cavities h h' in said spindle for the reception of the tool or tool-carrier, substantially as described.
- 20

4. The combination of the casing, the driving-shaft mounted therein, shaft F, gear-wheel D, and pinion E, meshing therewith, a worm E', and worm-wheel G, a spindle H, on which the worm-wheel is mounted, said spindle being adapted to bearings in the casing, and the tool-cavities in said spindle, with nuts i i at each end of the spindle, substantially as and for the purpose set forth.

5. The combination, in a reaming or tapping machine, of the spindle, gearing therefore, said spindle having its ends screw-threaded, and a tool-carrier adapted to said screw-threaded portion of the spindle, substantially as set forth.

In testimony whereof I have signed my name to this specification in the presence of two subscribing witnesses.

FREDERIC SCHOFF.
